Primary Examiner — Rosemary K Tarcza*(74) Attorney, Agent, or Firm* — Thomas P. O'Connell;
O'Connell Law Firm(57) **CLAIM**

We claim the ornamental design for a dual-bay battery charger, as shown and described.

DESCRIPTION

FIG. 1 is a perspective view of a dual-bay battery charger showing our design with a first battery received into a battery bay and a second battery positioned for insertion into a battery bay, the batteries forming no part of the claimed design;

FIG. 2 is a top plan view thereof;

FIG. 3 is a bottom plan view thereof;

FIG. 4 is a view in rear elevation thereof;

FIG. 5 is a view in front elevation thereof;

FIG. 6 is a view in left side elevation thereof; and,

FIG. 7 is a view in right side elevation thereof.

The batteries and the port shown in broken lines are for illustrative purposes only and do not form a part of the claimed design.
